Primary Examiner — Joseph Kukella*Assistant Examiner* — Darryl J Dardenne(74) Attorney, Agent, or Firm — Grogan, Tuccillo & Vanderleeden LLP(57) CLAIM

The ornamental design for a coffee maker as shown and described.

DESCRIPTION

FIG. 1 is a perspective view of a coffee maker showing a new design;

FIG. 2 is a front elevational view thereof;

FIG. 3 is a rear elevational view thereof;

FIG. 4 is a left side elevational view thereof;

FIG. 5 is a right side elevational view thereof; and

FIG. 6 is a top plan view thereof; and,

FIG. 7 is a bottom plan view thereof.

The broken lines in the figures illustrate portions of the coffee maker which form no part of the claimed design.

1 Claim, 5 Drawing Sheets(56)
